vs. Pierce & Fisher
et al.

UNITED STATES PATENT OFFICE.

HERBERT H. HEWITT, OF BUFFALO, NEW YORK.

CAR-AXLE JOURNAL-BOX.

1,072,719.

Specification of Letters Patent.

Patented Sept. 9, 1913.

Application filed July 8, 1910. Serial No. 571,071.

To all whom it may concern:

Be it known that I, HERBERT H. HEWITT, a citizen of the United States, and a resident of Buffalo, county of Erie, and State of New York, have invented certain new and useful Improvements in Car-Axle Journal-Boxes, of which the following is a full, clear, and exact description.

The present invention relates to car-axle journal boxes and seeks to provide means for effectively lubricating the axle journals, and, further, to provide improved means for preventing the leakage of lubricant from the journal box and the access of dust, dirt, or the like thereto, the improved construction being more particularly applicable to the car-axle journal box set forth and claimed in an application for Letters Patent filed in the United States Patent Office, March 7, 1910, Serial No. 547,862.

The invention consists in the novel features hereinafter set forth, illustrated in the preferred form in the accompanying drawings and more particularly pointed out in the appended claims.

In the drawings, Figure 1 is a view in central vertical section of one of the wheels of the car truck, the car-axle being shown in elevation and the parts of the journal box in section. Fig. 2 is a view in vertical section on the line 2-2 of Fig. 1. Fig. 3 is a detail perspective view of the guard ring for the journal box. Fig. 4 is a detail section on the line 4-4 of Fig. 1, and Fig. 5 is a detail perspective view of the cap or thimble for closing the opening at the outer end of the journal box.

A designates a car wheel that is fixed in the usual manner to the car-axle B. As shown, the end of the axle is reduced to form journal B' that is encircled by a bearing sleeve C contained within the journal box D. The journal box D is provided with a cylindrical opening to receive the sleeve C. Preferably, the box is formed of a single part and is spherical in shape, as shown. The box is held in place within an opening formed in the side frame E of the car truck by annular keepers or retaining rings F. These retaining rings are screw-threaded into the opening of the side frame and are provided with semi-spherical faces to properly engage the spherical body portion of the journal box. At their outer portions, the retaining rings are provided with flanges which abut against a flange e formed on the

side frame about the opening. By this arrangement the journal box D is securely held against lateral movement, but is free to shift universally within its seat or socket. At the same time it is free to rotate or creep within the retaining members or rings F, so that different portions of the journal box and bearing sleeve C therein are brought to a position to sustain the thrust of the journal B' of the car-axle.

For lubricating the journal box, it is provided at its outer end with a chambered projection D', which is preferably formed in piece with the journal box. In the form shown, the projecting portion D' is semi-spherical and a series of transverse webs d' are cast within the chamber therein. There are three of these webs in the form shown and the central portions thereof are cut away to form space for a cap or thimble G, which normally closes a central opening in the projection or lubricant containing part D'. The cap G is provided with a series of offsets or lateral projections g and the spring H normally holds the cap in position to close the opening in the chambered part D' with the projections g engaging the inner edge of the opening. The projections or offsets g are preferably in the form of metal tongues stamped or punched outwardly from the wall of the cap G. Such tongues or offsets will have sufficient elasticity, so that, when the cap is punched in through the opening in the chambered part D', the tongues g' will spring outwardly to engage the inner wall of the chambered part D'. The spring H has its outer portion located, within cap or thimble G, while its inner end bears against the metal that unites the several webs d', as shown in Figs. 1 and 4 of the drawings. When the cap G is first introduced into the opening of the chambered part D', the resilient or elastic tongues g' thereon are first pressed inwardly and then spring outward to engage the inner wall of the chambered part D', to thereby hold the spring H under compression and prevent the escape of the cap or thimble G from the opening in the chambered part D'. The part D' thus forms a suitable chamber for receiving grease or thick oil for lubricating the journal box. By pushing the cap or thimble G inwardly, the chamber of the part D' can be filled with grease or like lubricant. The cap is then automatically restored to the position shown to prevent

the escape of lubricant and the entrance of dust and dirt to the journal box.

The bearing sleeve C, which is rotatable within the journal box D, abuts against a shoulder d^2 at the outer end of the chamber of the journal box. The inner end of the bearing sleeve coincides with the reduced inner end d^3 of the journal box. That is to say, the inner end faces of the bearing ring C and journal box D lie in the same plane and are arranged to be engaged by a single guard ring K. This guard ring can be made of any suitable metal and is mounted upon the reduced portion 10 B' of the axle B, this reduced portion extending as shown to the hub a of the wheel A. The outer face of the guard ring is machined to accurately bear upon the inner ends of the journal box D and of the bearing sleeve C. Preferably, the guard ring K is slightly larger in diameter than the end portion of the journal box, so that it shall at times securely close the end of the journal box and prevent the access of dust and 15 dirt thereto and also prevent the escape of any excessive amount of lubricant therefrom. By this arrangement, the snug bearing of the guard ring K against the ends of the bearing sleeve and journal box will 20 effectively prevent the waste of lubricant, even though the internal diameter of the bearing sleeve C is increased by wear, or if the journal portion of the axle is reduced by wear. So also the bearing of the 25 guard ring uniformly upon the ends of both the journal box and bearing sleeve will prevent the escape of lubricant, notwithstanding the wear of the ends of such parts. The coincidence of the inner end of the bearing sleeve and the inner end of the bearing box also insures that both these parts shall 30 take the thrust and wear incident to the lateral movement of the truck.

The guard ring is provided, in the preferred form of the invention, with a series of chambers or pockets k, which are open at their inner ends and arranged to receive a series of coiled springs L. The inner ends of these springs bear upon the hub a on the 35 wheel A, and, as the springs are under compression, they serve to force the guard ring K outwardly and into a snug bearing with the inner ends of the journal box D and bearing sleeve C. The thickness of the 40 guard ring G is sufficiently less than the distance between the inner end of the journal box D and the hub a of the car wheel to permit a lateral play (say of about one-half inch of the journal). In case of a 45 violent lateral motion of the truck, it will be found that the springs L will take the first impact and then the hub of the wheel A will be brought up solidly against the ring K, the springs being forced into the 50 chambers k of the ring, and further lateral

movement of the journal will be prevented as the shoulder b of the axle B will at the same time contact with the inner face of the ring K. The guard ring thus not only serves to exclude dust and like foreign matter from the journal box, but, with its springs L also serves to cushion the shocks incident to the lateral movements of the truck and thereby reduces the strain and wear upon the parts. 75

The lubricant within the chamber of the part D' passes between the journal B' and the bearing sleeve C, and, also between the bearing sleeve and the journal box D to lubricate the contacting surfaces of these 80 parts. The lubricant works through the bearing sleeve and journal box to the inner ends thereof, but any waste of lubricant at this point is prevented by the guard ring K.

The journal B' is not only revoluble 85 within the sleeve C, but the latter can rotate or creep within the journal box D, and, in a similar manner, the journal box itself may rotate or creep within its bearing, so that new wearing surfaces are constantly 90 presented, thereby greatly prolonging the life and effectiveness of the parts.

This improved journal box is set forth and claimed in the prior application referred to, Serial No. 574,862. 95

The present invention provides effective means for lubricating the improved journal box and for preventing the escape of lubricant therefrom or the admission of dust and dirt thereto. In practice, it will 100 be found, that the thin film of lubricant escaping from the inner end of the journal box will pass around the outer spherical surface thereof and sufficiently lubricate the contacting surfaces of the box and of the 105 retaining rings F.

It is obvious that the details set forth may be varied without departure from the essentials of the invention as defined in the claims. 110

Having thus described my invention, what I claim as new, and desire to secure by Letters Patent, is:—

1. The combination with a car axle having a wheel fixed thereto, and a projecting end journal, a car axle journal box having a cylindrical chamber therein to receive said journal, a bearing for said journal within said cylindrical chamber, a support wherein said car axle journal box is rotatably mounted, said journal box being provided at its outer end with a projecting, semi-spherical portion extending over the end of said chamber, said portion being hollow to form a lubricant receptacle, smaller in 120 diameter than said chamber, and having an axial opening therein and an outwardly spring pressed device for closing said opening, substantially as described.

2. A car axle journal box chambered to 130

receive a journal and its bearing and provided at its outer end with a hollow projecting portion extending over the end of said chamber and having an axial opening 5 for the admission of lubricant, a sheet metal cap for closing said opening having integral, forwardly extending and laterally projecting fingers for engaging the edges of said opening, and a spring for pressing said 10 cap outwardly.

3. A car axle journal box chambered to receive a journal and its bearing and provided at its outer end with a hollow projecting portion forming a lubricant chamber, said portion having internal transverse 15

webs and an opening for the admission of lubricant, a sheet metal cap for closing said opening, said cap being arranged within said lubricant chamber and guided by said webs, and a spring for pressing said cap 20 outwardly, said sheet metal cap having laterally projecting fingers engaging the edges of said opening for limiting the outward movement of the cap, substantially as described.
